NO. 12,128

JAN 18, 1881

JOHN K. ROGERS' NEW DESIGN OF PRINTING TYPES.

PERFORMANCE IN THE AFTERNOON

BOSTON THEATRE

UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,128, dated January 18, 1881.

Application filed September 23, 1880. Term of patent 3½ years.

To all whom it may concern:

Be it known that I, JOHN K. ROGERS, of the town of Brookline, in the State of Massachusetts, have invented and produced a new and original Design for a Font of Printing-Types, of which the following is a specification, the nature of the design being clearly shown in the accompanying typographical impressions, to which reference is made.

My design consists of nine end and connecting pieces.

The letters, points, and figures are not new.

The nine end and connecting pieces may be described as follows: Nos. 1 and 9 are right

and left end pieces. Nos. 2 and 8 are also right and left end pieces, as shown; No. 3, an up-and-down line; No. 4, a right-hand end piece; No. 5, a left-hand end piece; No. 6, a space, and No. 7 a connecting-piece, all with top and bottom connecting-lines.

I claim as new and desire to secure by Letters Patent—

The design for a font of printing-type, as herein shown and described.

JOHN K. ROGERS.
